SILAS SCHOFIELD, OF PLAINVILLE, MASSACHUSETTS.

Letters Patent No. 69,845, dated October 15, 1867.

IMPROVEMENT IN TATTING-SHUTTLE.

The Schedule referred to in these Letters Patent and making part of the same.

TO ALL WHOM IT MAY CONCERN:

Be it known that I, SILAS SCHOFIELD, of Plainville, in the county of Norfolk, and State of Massachusetts, have invented a new and useful Improvement in Ladies' Tatting-Shuttle; and I do hereby declare that the following is a full, clear, and exact description thereof, which will enable those skilled in the art to make and use the same, reference being had to the accompanying drawings, forming part of this specification.

This invention relates to a new and improved method of constructing what is called a ladies' "tatting-shuttle," an instrument in common use for weaving or knitting a narrow kind of trimming for linen garments; and the invention consists in attaching it to a holder and providing for winding the thread on to the shuttle by a key or crank, thereby greatly facilitating the operation, as will be hereinafter described.

Figure 1 represents a side view of the shuttle with the holder attached, and

Figure 2 is a sectional edge view of the same, showing the key or crank by which the shuttle is turned in the holder in the process of winding the thread, the section being through the line *x x* of fig. 1.

Similar letters of reference indicate corresponding parts.

A is the shuttle, *B* is the holder, and *C* is the crank. *d* is the centre of the shuttle. The sides of the shuttle are raised or bossed on the outside, as seen in the drawing, with holes of any suitable shape and size passing through the boss. The handle is a spring-clasp, with holes through the ends, which fit on to the bossed sides of the shuttle, as seen in the drawing. The spring of the handle or clasp keeps it in place on the shuttle when it is in use. The end of the crank *C* is made to fit the hole through the shuttle, so that, by slipping on the handle and inserting the crank, the shuttle is turned or revolved within the holder, thus winding on the thread with great rapidity. The thread may be wound on to the shuttle as tightly as may be desired, as the tension of the thread can be governed by the thumb or finger on the handle. When the winding is completed the handle is slipped off the shuttle, the crank is removed, and the shuttle is ready for use. The centre or eye of the shuttle is a ring, to which the sides are attached. This centre may be a solid piece, with a square or other shaped hole through it, and when the shuttle is made of certain material (as wood or horn) the shuttle may be formed of one piece.

I do not confine myself to a particular material, nor to any particular manner of constructing the shuttle, but what I claim, and desire to secure by Letters Patent, is—

1. A tatting-shuttle, provided with a detachable handle or holder *B*, substantially as and for the purpose specified.

2. A tatting-shuttle, provided with mechanical means for winding the thread upon it, substantially as herein shown and described.

3. In combination with the shuttle *A*, the holder *B*, crank *C*, and the crank-bolt *i*, the whole arranged substantially as and for the purpose specified.
